UNITED STATES PATENT OFFICE.

WILLIAM D. McNAULL, OF TOLEDO, OHIO, ASSIGNOR TO THE McNAULL AUTO TIRE COMPANY, OF TOLEDO, OHIO, A CORPORATION.

DESIGN FOR A TIRE-TREAD.

48,981.

Specification for Design.

Patented May 2, 1916.

Application filed October 19, 1914. Serial No. 867,546. Term of patent 14 years.

To all whom it may concern:

Be it known that I, WILLIAM D. McNAULL, a citizen of the United States residing at Toledo, in the county of Lucas, State of Ohio, have invented a new, original, and ornamental Design for Tire-Treads, of which the following is a specification, reference being had to the accompanying drawing, forming part hereof.

Figure 1 is a plan-view of said design,

and Fig. 2, a cross sectional elevation taken on line $x-x$, Fig. 1 of a tire showing my new design.

I claim:

The ornamental design for a tire tread as shown.

WILLIAM D. McNAULL.

Witnesses:

E. C. FROEHLICH,
GERTRUDE BRACKER.
